UNITED STATES PATENT OFFICE.

ALICE LOUISE HAPGOOD, OF BELLOWS FALLS, VERMONT.

MEASURE.

SPECIFICATION forming part of Letters Patent No. 783,862, dated February 28, 1905.

Application filed October 3, 1904. Serial No. 226,979.

To all whom it may concern:

Be it known that I, ALICE LOUISE HAPGOOD, a citizen of the United States, residing at Bellows Falls, in the county of Windham and State 5 of Vermont, have invented a new and useful Measure, of which the following is a specification.

This invention applies to measures.

The object of the invention is to present an 10 implement of the class described for use in dry goods and other stores which may be adjusted to cut goods on the bias with accuracy and precision and in predetermined widths, which may be employed for plattting and laying out 15 dressmaker's work—such as the cutting and fitting of skirts, trimmings, and the like—and, further, which may have its parts combined in such manner as to present a continuous and straight measuring implement or be folded or 20 collapsed to occupy but small space when carried about.

With the above and other objects in view, as will appear as the nature of the invention is better understood, the same consists in the 25 novel construction and combination of parts of an adjustable and foldable bias-measure, as will be hereinafter fully described and claimed.

In the accompanying drawings, forming a 30 part of this specification, and in which like characters of reference indicate corresponding parts, there is illustrated one form of embodiment of the invention capable of carrying the same into practical operation, it being understood that the elements therein exhibited may 35 be varied or changed as to shape, proportion, and exact manner of assemblage without departing from the spirit thereof.

In the drawings, Figure 1 is a view in elevation, exhibiting the implement when set for 40 cutting goods on the bias. Fig. 2 is a similar view showing the implement set for measuring or marking goods of extra width. Fig. 3 is a transverse sectional view taken on the line 3 3, Fig. 1, and looking in the direction of the 45 arrow thereon. Fig. 4 is a similar view taken on the line 4 4, Fig. 1, and looking in the direction of the arrow thereon. Fig. 5 is a perspective view exhibiting the implement folded or collapsed.

50 The implement, as shown in Figs. 1 and 2,

comprises five adjustably-connected members 1, 2, 3, 4, and 5. The member 1, which constitutes a length-scale and which by preference will be made about thirty-nine inches long, is graduated in inches and parts thereof, preferably according to the English scale, the graduation-marks being disposed at right angles to the length of the member, while the members 2 and 3, which constitute width-scale members and are preferably about nine inches in length, 55 are also graduated in inches and parts of inches, having their graduation-marks disposed at an angle of about forty-five degrees to the length of the members. The two members 4 and 5, which constitute extension members and 60 which are preferably twenty-seven inches in length, have their graduation-marks disposed at right angles to their length, and each is provided with a longitudinal slot 6 and 7, respectively, which extends throughout the greater 65 portion of the length of the member and terminates at such distances from the ends thereof that when the parts of the implement are adjusted as shown in Fig. 1 the ends of the members 4 and 5, which are beveled preferably at 70 an angle of forty-five degrees to their length, will coincide or aline with the outer edges of the members 2 and 3, and when this adjustment is effected the user will know that the implement is set for cutting goods on a true bias. 75 The members 2 and 3 are each also provided with a longitudinal slot 8 and 9, respectively, which terminates at such distances from the terminals of the two members that when the members are moved to their limit, as when 80 the parts are in the position shown in Fig. 1, the terminals, which, as before stated, are beveled at an angle of forty-five degrees to their length, will aline with the outer edge of the member 1 and also with its terminals, which 85 are also beveled at forty-five degrees to the length of the member. In other words, by having the terminals of all the members beveled at forty-five degrees to their length when the implement is set and all these ends coincide 90 or aline with each other the operator will know that the implement is set for cutting exactly on the bias. To effect different adjustments of the members 2 and 3 with relation to the member 1, the latter is provided 95 100

at each end with a slot 10 and 11, respectively, which will permit of the members 2 and 3 being adjusted at other angles than forty-five degrees should necessity therefor arise, as 5 when platting or laying out dress-patterns or for other uses.

All the parts are held assembled for ready adjustment by means of bolts 12, of which there are five in number, each of which carries a thumb-nut 13. The head 14 of the bolt is turned down or formed very thin in order to lie close against the under sides of the members 1, 2, and 3, thus to bring the scales close to the work to be measured, and a length of 15 each bolt equal to the thickness of one of the members is squared, as at 15, to prevent it from turning in the slot of the member with which it coacts when the thumb-nut is being tightened.

20 By the manner of constructing the different parts of the implement the same is capable of being adjusted for effecting the platting of a great variety of work and also for measuring or marking goods of extra length, which may be effected by loosening two of the thumb-nuts that hold the member 6 combined with the member 7 and then sliding the former outward to the position shown in Fig. 2. Should a straight measure of considerable length be 25 desired for any purpose, all of the parts may be connected for this purpose.

While the various proportions of the different members herein exhibited have been found effective for general use, it is to be understood that the invention is not to be limited thereto, as these proportions may be varied or changed as found necessary or de- 30

sirable and still be within the scope of the invention.

Having thus described the invention, what 40 is claimed is—

1. An implement of the class described comprising a graduated length-scale member having slotted terminals, graduated width-scale members having longitudinal slots, longitudinally-slotted extension members, and means for adjustably connecting all of the members. 45

2. An implement of the class described comprising a length-scale member having slotted terminals and graduation-marks disposed at 50 right angles to the length of the member, width-scale members having longitudinal slots and graduation-marks disposed at an angle of forty-five degrees to their length, longitudinally-slotted extension members having graduation-marks extending at right angles to their 55 length, and means for adjustably connecting all the members.

3. An implement of the class described comprising a graduated length-scale member having slotted terminals, graduated width-scale members having longitudinal slots, longitudinally-slotted extension members, and means for adjustably connecting all of the members, the terminals of all the members being disposed at an angle of forty-five degrees to their 60 length.

In testimony that I claim the foregoing as my own I have hereto affixed my signature in the presence of two witnesses.

ALICE LOUISE HAPGOOD.
